UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,330,252.

Specification of Letters Patent. Patented Feb. 10, 1920.

Application filed January 2, 1918. Serial No. 209,966.

To all whom it may concern:

Be it known that I, CLARENCE B. FOWLER, a citizen of the United States, residing at New York, in the county of New York, State of New York, have invented certain new and useful Improvements in Telephone-Exchange Systems, of which the following is a full, clear, concise, and exact description.

10 This invention relates to telephone exchange systems and more particularly to such systems of the control energy type in which both local and rural subscribers' lines terminate at the same central office, the former being equipped for both common battery signaling and talking, and the latter for common battery signaling and local battery talking.

It is an object of the present invention to 20 provide improved signaling means for systems of this character.

In accordance with one feature of this invention, a link circuit for interconnecting telephone lines of the types mentioned is 25 provided with two relays one of which operates upon connection with a rural subscriber's line and coöperates with a supervisory or subscriber controlled relay for controlling a supervisory signaling device, and 30 the other of which operates upon connection with a local subscriber's line and coöperates with the supervisory relay to control the supervisory signaling device.

For a more complete understanding of 35 this invention, reference should be had to the following description considered in connection with the accompanying drawing illustrating one embodiment thereof.

As shown in the drawing, a local telephone 40 line A extends to and may be connected in any well known manner with a cord circuit C, the calling end of which is equipped with apparatus for carrying into effect the purposes of this invention. The calling end of 45 this cord circuit may connect with either a rural subscriber's line B or a local subscriber's line D. A local subscriber's line is one which is equipped for both common battery signaling and talking, while a rural 50 subscriber's line is equipped for common battery signaling and local battery talking. The cut-off relay of the rural line is of high resistance so that a marginal relay associated with the link circuit will not respond

upon connection with the rural line, but will 55 operate when connection is made with the local line which has a cut-off relay of low resistance. It is thought that this invention may be best understood from a description of the operation of the system disclosed in 60 the drawing and it will be so described.

Subscriber A having initiated a call and the cord circuit C having been connected therewith, the operator actuates the listening key 5 to connect the telephone set with 65 the calling line. The operator upon being advised that connection is desired with a local subscriber's line, for example line D, restores the listening key 5 to normal position and inserts calling plug 6 into line 70 jack 7 of line D. Relays 8, 9 and 10 of the cord circuit and cut-off relay 11 of line D are thereupon operated over a circuit from battery through the lower winding of relay 8, the winding of relay 10, the winding of 75 marginal relay 9, the upper winding of relay 8, sleeve contacts of the plug 6 and the jack 7 and winding of the cut-off relay 11 to ground. While relay 10 operates to establish a circuit for the supervisory lamp 80 12, this circuit is only maintained for an instant and is of no effect, for the marginal relay 9 operates at the same time as relay 10 and in so doing opens the energizing circuit of the relay 10. Marginal relay 9 85 thereupon establishes a locking circuit for itself from battery through the supervisory lamp 12, upper alternate contact and winding of relay 9, the upper winding of relay 8, sleeve contacts of the plug 6 and jack 7 90 and the winding of the cut-off relay 11 to ground. The supervisory lamp 12 is thereupon lighted. Relay 8, in operating, closes its contacts, the closure of the upper contact extending the tip of the calling plug to a contact of ringing relay 13. The operation of the cut-off relay 11 disconnects the usual line relay from the line. Marginal relay 9, in operating, also opens its lower normal contact which is in an energizing circuit of a slow-to-operate relay 14. The closure of the lower alternate contact of relay 9 causes the operation of a slow operating relay 15 over a circuit from battery through the winding of relay 15, lower 100 alternate contact of relay 9, lower normal contact of relay 14 and lower contact of relay 8 to ground. Ringing relay 13 is 105

- thereupon energized over the circuit from battery through the winding of ringing relay 13, normal contact of relay 25, normal contact of trip relay 16, contact of relay 15, lower normal contact of relay 14 and lower contact of relay 14 and lower contact of relay 8 to ground. Ringing relay 13, in operating, connects ringing current to line D over a circuit from the source of ringing current 20 through the winding of trip relay 16, lower alternate contact of ringing relay 13, ring contacts of the plug 6 and the jack 7, over one side of the line, through the usual call bell connected with the line at the station of line D, back over the other side of the line, tip contacts of the jack 7 and plug 6, upper contact of relay 8, and upper alternate contact of ringing relay 13 to ground. A portion of this ringing current passes through condenser 21, which bridges the now open lower normal contact of ringing relay 13 and then passes through a winding of the repeating coil, whereupon a ringing indication is transmitted to the calling party.
- The called subscriber in responding to the operation of the call bell removes the receiver from the switch hook, thereby causing the operation of trip 16 which opens its contact, removing the short circuit from the winding of relay 25. Relay 25 thereupon operates, establishing a temporary locking circuit for itself through its left-hand alternate contact, and, in so doing, establishes a short circuit for the ringing relay 13. Ringing relay 13 thereupon releases its armatures, disconnecting ringing current from the line and closing its normal contacts which are in the talking circuit. Relay 25 in operating also causes the operation of relay 14 over the circuit from battery through the winding thereof, and the right-hand contact of relay 25 to ground. Relay 14 in operating closes the contact in the ring talking strand of the cord circuit C, opens the energizing circuits of relays 15 and 25, and establishes a locking circuit for itself through its lower alternate contact and the lower contact of relay 8 to ground.
- The release of relay 25 does not complete an energizing circuit for the ringing relay 13 for the contact of relay 15 and the lower normal contact of relay 14 are now open. Supervisory relay 22 is operated upon the closure of the upper alternate contact of relay 14 and in operating establishes a shunt circuit about the lamp 12 which includes the resistance 23, thereby extinguishing this lamp.
- At the conclusion of the conversation, restoration of the receiver to the switchhook by subscriber D causes the release of supervisory relay 22, whereby the shunt circuit of the lamp is opened and the lamp is lighted to furnish the disconnect signal.

The operator may thereupon withdraw the plug 6 from the jack 7, whereupon all apparatus is restored to normal condition.

Should subscriber A desire to be connected with a rural line, for example line B, the insertion of the calling plug 6 into jack 30 of line B, causes the operation of relays 8 and 10 of the cord circuit and cut-off relay 31 of the line circuit. The supervisory lamp 12 is lighted by the operation of relay 10. Marginal relay 9 does not operate, due to the high resistance of the winding of the cut-off relay 31. Upon the operation of relay 8, relay 14 operates over a circuit from battery through the winding of relay 14, the lower normal contact of marginal relay 9, lower normal contact of relay 14 and the lower contact of relay 8 to ground. Relay 14 in operating establishes a circuit connection between a ringing key 32 and the rural line B so that upon the actuation of the ringing key 32, ringing current from the source 33 is connected to line B. The two sources of ringing current 20 and 33 may be and in practice usually are the same alternating current generator. Relay 14 in operating also establishes for itself the hereinbefore traced locking circuit. Upon the response of the called subscriber, supervisory relay 22 is operated to extinguish the supervisory lamp 12 in the manner hereinbefore described.

From the above description, it will be understood that when connection is made with a rural line, relay 10 functions to cause the supervisory lamp 12 to light, and supervisory relay 22 subsequently responds to extinguish this lamp. Therefore, when connection is made with a rural line, these two relays coöperate to control the supervisory lamp. When connection is made with the local line, however, relay 9 responds to cause the lighting of the supervisory lamp, and the same supervisory relay 22 later responds to extinguish the lamp. Therefore, when connection is made with a local line, relay 9 then coöperates with the same supervisory relay to control the supervisory lamp.

What is claimed is:

1. A telephone exchange system comprising local and rural subscribers' lines, a link circuit for interconnecting the lines, a signaling device in the link circuit, electromagnetic means in the link circuit responsive to the connection thereof with the rural subscriber's line to cause the operation of the signaling device, an electromagnetic switching device in the link circuit responsive to the connection thereof with a local subscriber's line for operating the signaling device, and means controlled over a line of either character for stopping the operation of the signaling device.
2. A telephone exchange system comprising

ing local and rural subscribers' lines, a link circuit for interconnecting such lines, a signal lamp in the link circuit, means in the link circuit responsive to the connection 5 thereof with the rural subscriber's line to light the signal lamp, means in the link circuit responsive to the connection thereof with a local subscriber's line for lighting the signal lamp, a relay in the link circuit 10 controlled over a line of either character for extinguishing the signal lamp.

3. A telephone exchange system comprising local and rural subscribers' telephone lines, a link circuit for interconnecting the

lines, a supervisory signal lamp in the link 15 circuit, a local circuit relay in the link circuit responsive to the connection thereof with a rural subscriber's line for lighting the lamp, a second local circuit relay in the link circuit responsive to the connection 20 thereof with the local subscriber's line for lighting the lamp, and a supervisory relay in the link circuit controlled over a line of either character for extinguishing the lamp.

In witness whereof I hereunto subscribe 25 my name this 28th day of December A. D., 1917.

CLARENCE B. FOWLER.
